TOOL

Jacob Baumgarten, Brooklyn, N. Y., assignor of
50 per cent to Saltser & Weinsier, Inc., New
York, N. Y., a corporation of New York

Application May 4, 1935, Serial No. 19,896

1 Claim. (Cl. 81—71)

This invention relates to tools and has special reference to a compound wrench used to unscrew plumbing or other parts which are inaccessible with the ordinary tool.

- 5 One important object of the invention is to provide a novel form of compound wrench so constructed that whenever one of the wrench members is in active use the remaining members are used to actuate the active member.
- 10 A second important object of the invention is to provide a novel form of compound wrench especially adapted for use selectively as a half socket or spanner wrench or a screw driver wrench.
- 15 In using a half socket wrench it is desirable to forcibly hold the wrench in engagement with the bolt or nut being turned and it is a third important object of the invention to provide an improved form of such wrench having a screw driver part arranged to receive pressure from the operator's hand to hold the spanner element properly and safely in engagement and against slipping off the part being turned.
- 20 With the above and other objects in view, as will be presently explained, the invention consists in general of certain novel details of construction and combinations of parts hereinafter fully described, illustrated in the accompanying drawing and specifically claimed.
- 25 In the accompanying drawing like characters of reference indicate like parts in the several views, and:—

Figure 1 is a side elevation of the improved wrench.

30 Figure 2 is a plan view thereof.

Figure 3 is a detail section on the line 3—3 of Figure 2.

Figure 4 is a detail end view of a part of the wrench member at the left hand end of Figure 1.

40 In the embodiment of the invention as here illustrated there is provided a flat bar 10 of greater width than thickness, the bar and all other parts of the wrench being formed integral- 40 ly of rigid metal. At one end of this bar there is provided a curved projection 11 which is arcuate in cross section and at its other end there is provided a second curved projection 12 also arcuate in cross section and provided on its arcuate working edge with a notch 13. These members 11 and 12 have parallel axes and these axes are arranged at obtuse angles to the plane of the flat bar 10. The member 11 has vertical edges 14 which lie in planes substantially radial to the axis of this member while the member 12 is likewise provided with vertical edges 15 lying in planes radial to the axis of the member 12. Projecting from one edge of the bar 10 is a screw driver blade 16 for slotted bolts, pipe caps and the like, the member being thus a species of screw

driver. This member 16 is of general trapezoidal form with the narrower part joining the bar 10 so that the blade 16 can be gripped conveniently with the fingers of the operator at the corners where the blade 16 meets the flat bar 10. The member 16 is also provided with rectangular notches 17 in its corners forming limiting shoulder portions. The member 16 lies throughout in the plane of the bar 10 so that it forms practically a widening of the bar 10 at the place at which it projects from the bar 10.

5 It is to be observed that whenever the member 11 or the member 12 is in active use the remaining member, due to its parallel and oppositely disposed position, constitutes a crank handle for 15 rotating the member in use. Furthermore, when the operator uses one of the members 11 and 12 as a crank handle by grasping it with one hand, he places his remaining hand on the member 16 and the adjacent portion of the bar 10 and ex- 20 erts pressure thereon to hold the engaged member 11 or 12 from slipping off the article with which it is engaged.

Similarly, when the member 16 is in active use the two members 11 and 12 form hand grips by 25 means of which the member 16 may be both rotated and forcibly held engaged with the article to be turned.

Thus in using any one of the members with which the tool is provided, the remaining mem- 30 bers act as holding and turning elements for the used member.

35 There has thus been provided a simple and efficient device of the kind described and for the purpose specified.

It is obvious that changes may be made in the form and construction of the invention without departing from the material principles involved. It is not therefore desired to confine the invention to the exact form herein shown and de- 40 scribed but it is desired to include all such as come within the scope of the matter claimed.

What is claimed is:

In a device of the kind described comprising a flat bar, curved projections at opposite ends of 45 the bar and extending in opposite directions from each other at an obtuse angle with respect to the bar, a screw driver blade projecting laterally from the bar and adjacent one end thereof and being in the same plane therewith, said blade extending 50 transversely to the curved projections, the blade tapering outwardly from the bar toward its free end and being provided at its free end with a reduced portion forming limiting shoulders whereby the side of the bar and a tapering side of the 55 blade act as a finger rest when the device is in use.

JACOB BAUMGARTEN.
